(57) **CLAIM**

I claim the ornamental design for a textured prophylactic, as shown and described.

DESCRIPTION

FIG. 1 is a perspective view of a first embodiment of a textured prophylactic.

FIG. 2 is a side view of the first embodiment of a textured prophylactic.

FIG. 3 is a top view of the first embodiment of a textured prophylactic.

FIG. 4 is a bottom view of the first embodiment of a textured prophylactic.

FIG. 5 is a magnified version of the top view shown in FIG. 3 for the first embodiment of a textured prophylactic.

FIG. 6 is a magnified version of the bottom view shown in FIG. 4 for the first embodiment of a textured prophylactic.

FIG. 7 is a perspective view of a second embodiment of a textured prophylactic.

FIG. 8 is a side view of the second embodiment of a textured prophylactic.

FIG. 9 is a top view of the second embodiment of a textured prophylactic.

FIG. 10 is a bottom view of the second embodiment of a textured prophylactic.

FIG. 11 is a magnified version of the top view shown in FIG. 9 for the second embodiment of a textured prophylactic.

FIG. 12 is a magnified version of the bottom view shown in FIG. 10 for the second embodiment of a textured prophylactic.

FIG. 13 is a perspective view of a third embodiment of a textured prophylactic.

FIG. 14 is a side view of the third embodiment of a textured prophylactic.

FIG. 15 is a top view of the third embodiment of a textured prophylactic.

FIG. 16 is a bottom view of the third embodiment of a textured prophylactic.

FIG. 17 is a magnified version of the top view shown in FIG. 15 for the third embodiment of a textured prophylactic.

FIG. 18 is a magnified version of the bottom view shown in FIG. 16 for the third embodiment of a textured prophylactic.

FIG. 19 is a perspective view of a fourth embodiment of a textured prophylactic.

FIG. 20 is a side view of the fourth embodiment of a textured prophylactic.

FIG. 21 is a top view of the fourth embodiment of a textured prophylactic.

FIG. 22 is a bottom view of the fourth embodiment of a textured prophylactic.

(Continued)

FIG. 23 is a magnified version of the top view shown in FIG. 21 for the fourth embodiment of a textured prophylactic; and,

FIG. 24 is a magnified version of the bottom view shown in FIG. 22 for the fourth embodiment of a textured prophylactic.
